UNITED STATES PATENT OFFICE.

EDWARD H. ELLISON, OF JAMESTOWN, NEW YORK, ASSIGNOR TO ELLISON BRONZE COMPANY, INC., OF FALCONER, NEW YORK, A CORPORATION OF NEW YORK.

VENTILATOR.

Application filed August 24, 1926, Serial No. 131,184.

This invention relates to an improvement in a ventilator, and more particularly in a ventilator which permits the circulation of air while preventing the entry of light and which cannot be seen through.

The primary object of this invention is to provide a ventilator of the type specified, comprising a plurality of louvers rigidly mounted in a sash in two sets, one set on each side thereof, between which sets of louvers a plate is located which can be raised or lowered to admit air without permitting visibility or the entry of light.

A further object of this invention is to provide a ventilator of this type in which the sash is made up of two frames, to which frames the louvers are rigidly secured, one set of louvers to each frame, whereby each is complete in itself before it is assembled with the other to form the finished ventilator.

Other objects of this invention will appear from a consideration of the following description taken in connection with the drawings which form a part thereof, and in which

Fig. 1 is a front elevation of a ventilator embodying this invention;

Fig. 2 is a section taken along the line 2—2 of Figure 1, showing the ventilator open;

Fig. 3 is a view similar to Figure 2, the ventilator, however, being closed;

Fig. 4 is an enlarged cross section of the base of the ventilator;

Fig. 5 is a perspective view of the ventilator, broken away in part, to show the relation of the various elements;

Fig. 6 is a perspective view of the regulator plate and the mechanism for operating it;

Fig. 7 is a perspective view of the regulator plate per se;

Fig. 8 is a perspective plan view of the bottom plate;

Fig. 9 is a view of one of the louvers;

Fig. 10 is a section taken along the line 10—10 of Figure 3;

Fig. 11 is a sectional view taken along the line 11—11 of Figure 3; and

Figs. 12 and 13 are sectional plan views of the two frames which form the completed sash, each frame being provided with its louvers rigidly secured thereto.

Referring to the drawings, the reference numeral 20 is employed to designate the ventilator forming the subject of this invention, which comprises a rectangular sash 21 on which are mounted a plurality of louvers 22,

separated from each other, both horizontally and vertically, to provide transverse passages 23, and a central compartment 24. The louvers are divided into two sets, one on each side of the compartment 24. Within the compartment 24 is located a plate 25 provided with a plurality of slots 26 separated by imperforate portions 27, so arranged that when the plate is in the lower position, as shown in Figure 3, the portions 27 block the passages 23, so that the ventilator is closed, but when the plate is raised as shown in Figure 2 the slots 26 coincide with the passages 23 so that the ventilator is open.

The sash 21 is formed from a pair of frames 28 and 29. The frame 28 comprises bars 30 having an outwardly facing rectangular channel 31 provided with a lateral flange 32 extending at right angles thereto, which form the top and sides of the frame, and a Z-shaped bar 33, which forms the bottom. The frame 29 comprises bars 34, at the top and both sides, having an outwardly bracing channel 35 and a Z-shaped bar 36 at the bottom, which is the counterpart of the bar 33. The bars forming each frame are rigidly welded together, preferably at the corners along the lines 37. It is obvious, however, that other means for uniting the members of the frame could be employed, if desired.

The louvers 22 each comprise a vertical strip 40 and a curved skirt 41. The vertical strip 40 projects beyond the ends of the skirt 41 providing tongues 42. The louvers, as shown particularly in Figures 12 and 13, are secured in the frames 28 and 29, the projecting portions or tongues 42 being welded to the bars 30 and 34 along the inner walls of the channels 31 and 35.

After the frames 28, 29 have been made and the louvers 22 rigidly secured in place, the two frames which are shown in Figures 12 and 13, are assembled to form the sash 21 by welding the flanges 32 to the bars 34, as shown in Figure 10. This results in providing an inwardly facing channel 43 between the outwardly facing channels 31 and 35.

The flanges 32 are of sufficient width to separate the sets of louvers to provide the compartment 24 in which the slotted plate is free to reciprocate.

The lower edge of the plate 25 is cut away, as shown in Figure 7, to provide a rectangular recess 50 at the center and rec-

tangular tabs 51, 52 at each end. In these tabs 51, 52 are formed inclined slots 53, by means of which the plate 25 will be raised or lowered, as desired. A U-shaped strip 54 receives the tabs 51, 52 and carries rollers 55 suitably mounted upon rivets or pins 56 between the sides of the strip 54, which enter the slots 53. The strip 54 bears against the flanges 57 of the bars 33 and 36, so that it cannot move vertically, while through a slot 58 in the vertical wall of the bar 36 extends a handle 59 carried by the strip 54. Obviously by means of the handle 59 the strip 54 can be reciprocated, and as a result by reason of the interengagement of the slots 53 and rollers 55, the plate 25 will be raised or lowered when the strip 54 is reciprocated.

Moving the strip 54 to the left, as shown in Figure 1, will raise the plate 25 into the position shown in section in Figure 2, while moving the strip to the right will lower the plate 25. When the plate 25 is in the Figure 2 position the slots 26 coincide with the passages 23, while when the plate 25 is in the Figure 3 position, the imperforate portions 27 will coincide with the passages 23. Thus, the position of the plate 25 regulates the travel of air through the ventilator, but the louvers are so fixed that rays of light cannot pass directly through the ventilator and that the ventilator cannot be seen through in any position of the plate 25.

The bottom of the ventilator is closed by means of a channel plate 60, which is suitably secured by screws 61 or otherwise to the plates 33, 36. Mounted upon the plate 60, adjacent each end are bumpers 62, with which the strip 54 will contact as it reaches its limit of movement. In order to prevent the entry of flies, mosquitos or other insects suitable screening 63 may be secured to one face of the plate 25. It will be noted that any chance for light or vision through the ventilator at the joinder of the skirts 41 of the louvers with the bars 30 or 34 is prevented by the plate 25 at all times.

The ventilator embodying this invention is made and assembled as follows: The frames 28, 29 are first formed and then the louvers 22 are rigidly secured in place, being suitably spaced from each other to provide the passages 23. The frames 28 and 29 are then united to provide inwardly facing channels 43, into which the tongues 42 of the louvers extend, the strips 40 of the upper louvers extending into the upper channel 43, as shown particularly in Figures 2 and 3.

In the meantime the strip 54 is fixed upon the plate 25 by securing the rollers 55 in their position through the slots 53. The plate 25 and the strip 54 are then inserted in the compartment 24 between the sets of louvers 22 and the handle 59 is fixed to the strip 54 through the slot 58. The handle 59 functions not only as a handle, but also as a tem-

porary means for holding the plate 25 and strip 54 in the proper position in the ventilator. The channel bar 60 is then rigidly secured in place supplementing the action of the handle 59 in preventing the lowering of the strip 54. Referring particularly to Figure 4, it will be noted that the strip 54 is prevented from descending by means of the bar 60 and is prevented from ascending by means of the flanges 57. The ventilator is now complete and ready to be installed whenever it is desired.

It will be noted that the skirts 41 of each pair of louvers 22 extend below the edges of the passage 23, so that under no conditions is it possible to see through the ventilator. Moreover, by reason of the form of the skirts 41 it is impossible for direct rays of light to pass through the passages. At the same time, however, when the plate 25 is raised, the air can travel freely through the passages 23, and thus provide the desired ventilation.

The form of ventilator herein particularly shown and described is intended to be used in a door in place of one of the upper panels, thus eliminating the necessity of employing transoms previously found necessary in order to provide ventilation. The dimensions of the ventilator form no part of this invention, and it is obvious that the idea herein shown and described could be embodied in a ventilator for installation in a window or in any position whenever such a construction is desired.

While one embodiment of this invention has been shown and described applicant is not limited thereto, since it is obvious that other embodiments can be made without departing from the spirit and scope of this invention as set forth in the following claims.

Having thus set forth my invention, what I claim as new and for which I desire protection by Letters Patent is:

1. A ventilator comprising a sash having a continuous, inwardly facing channel therein, two sets of louvers extending into and rigidly secured in said channel and a plate mounted to reciprocate in said channel between said sets of louvers.

2. A ventilator comprising two frames joined to form a sash, a set of louvers rigidly secured to each frame before said frames are joined, a plate mounted to reciprocate in said sash between said sets of louvers, adjacent louvers of each set and corresponding slots in said plate providing passages and means for reciprocating said plate between the position in which the slots therein coincide with said passages to the position in which the portions of said plate between the slots coincide with said passages.

3. A ventilator comprising a sash having a continuous inwardly facing channel therein at three sides thereof, and spaced Z-shaped bars at the fourth side, sets of louvers one at

each side of said sash, each louver consisting of a downwardly extending skirt, and a vertical strip, the ends of which extend beyond the ends of said skirt into said channel and are fixed to said sash, a plate mounted to reciprocate vertically in said sash between said sets of louvers, a U-shaped strip mounted to reciprocate horizontally between said Z-shaped bars, said plate having inclined slots and rollers in said slots carried by said strip, whereby the horizontal reciprocation of said strip causes a vertical reciprocation of said plate.

4. A ventilator comprising a sash having a continuous inwardly facing channel therein at three sides thereof, and spaced Z-shaped bars at the fourth side, each bar having a flange projecting toward the space between,

sets of louvers one at each side of said sash, each louver consisting of a downwardly extending skirt, and a vertical strip, the ends of which extend beyond the ends of said skirt into said channel and are fixed to said sash, a plate mounted to reciprocate vertically in said sash between said sets of louvers, a U-shaped strip mounted to reciprocate horizontally between said Z-shaped bars below the flanges thereof, said plate having inclined slots and rollers in said slots carried by said strip whereby the horizontal reciprocation of said strip causes a vertical reciprocation of said plate.

In testimony whereof I have affixed my signature.

EDWARD H. ELLISON.
